UNITED STATES PATENT OFFICE.

ALBERT J. MARKS, OF NEW BRITAIN, CONNECTICUT.

NUMBERING-MACHINE.

1,395,722.

Specification of Letters Patent.

Patented Nov. 1, 1921.

Application filed January 12, 1921. Serial No. 436,779.

To all whom it may concern:

Be it known that I, ALBERT J. MARKS, a citizen of the United States of America, residing at New Britain, Hartford county, 5 Connecticut, have invented a new and useful Numbering-Machine, of which the following is a specification.

My invention relates to a numbering machine.

10 It is the general object of my invention to simplify the construction of machines of this type and to simplify the assembling of the various parts.

It is a special object to provide means for 15 holding the inking pad in a convenient position to be re-inked.

Other objects and advantages will appear as the specification proceeds.

In the drawings I have shown, merely by 20 way of illustration, a preferred form of my invention.

Figure 1 is a front elevation of a complete numbering machine;

Fig. 2 is a rear elevation thereof, parts being broken away;

Fig. 3 is a sectional view, taken substantially in the plane of the line 3—3 of Fig. 1 and showing the numbering head in its raised position;

30 Fig. 4 is a view similar to Fig. 3, but showing the numbering head in the depressed position;

Figs. 5 and 6 are detail views showing means for holding the numbering head in a 35 depressed position.

Fig. 7 is a perspective view showing various parts of the machine separated from each other; and

Fig. 8 is a fragmentary perspective view 40 showing means for holding the inking pad in convenient position to be re-inked.

In the illustrative form of machine shown there is provided a main U-shaped frame 5, having guideways 6 for guiding the number-

45 ing head in its reciprocation. The upper end of the main frame is provided with a hollow tube 7 for receiving the actuating rod of the numbering head and in which the spring 7' is partially housed. The usual 50 foot piece 8 may be secured to the bottom of the U-shaped frame, and a suitable thin plate 9, having an aperture therein to permit passage of the characters on the numbering

wheels, may be secured between the foot plate and legs of the frame. The parts thus 55 far described are usual in machines of this type.

The numbering head designated generally 10 is reciprocally mounted within the frame. This numbering head may include 60 a substantially U-shaped frame or yoke 11 having secured thereto the rod 12 for reciprocating the head. To the upper end of the rod 12 is secured a suitable knob 13 for actuating the numbering head, and the 65 spring 7' is interposed between the knob and a part of the main frame 5. It will be noted that the knob is suitably recessed to receive the tube 7 and the spring is housed and concealed therein.

70 The usual or any desired numbering wheels, such as 14, having thereon the proper characters, are mounted upon a shaft 15. These wheels are preferably resiliently held to said shaft so as to prevent their rotation 75 relatively to the shaft, except when actuated by the proper mechanism. Upon each end of the shaft I mount an end plate 16, at

least one of which is preferably non-rotatably mounted upon the shaft. In the 80 form shown I have provided a tongue 17 upon one of the plates, which co-operates with a corresponding keyway 18 in the shaft. It will be seen that the shaft carrying the 85 numbering wheels and the plates 16 may be handled as a unit, and the unit may be easily passed into the U-shaped yoke or frame 11. Means are provided for accurately positioning the numbering wheels and plates within 90 the yoke. In the drawings I have indicated lugs 19 projecting from the plates and recesses or apertures 20 within the numbering head yoke for receiving these lugs. The means shown may be sufficient to properly 95 secure the plates to the yoke, but I prefer to provide additional means, as will be later described.

A plate 21, preferably of sheet metal, covers one side of the numbering head frame, and the lower end may be curved, as 100 at 22, to conform in general to the shape of the numbering wheels for shielding a portion of the same from the pad proper of the inking device and providing a finished appearance.

105 When the numbering wheels and plates

have been assembled in the frame 11 and the cover 21 put in place, suitable pins or screws 23 (Fig. 3) may be passed through the apertures 24 (Fig. 7) in the cover 25 in the frame and 26 in the plates 16. The cover might, of course, be omitted, and the screws or pins would then merely hold the plates 16 in the frame.

The numbering wheels are actuated by a 10 comb mechanism designated generally 27. This comb mechanism may consist of a U-shaped yoke 28 carrying a proper comb with teeth, such as 29, for engaging parts of the numbering wheels for rotating the latter. 15 The arms of this yoke 28 are passed around the outside of the numbering head frame, and suitable pins or screws 30 pivotally secure the comb yoke in place on the numbering head, the pivots being preferably concentric with the shaft 15. A suitable roller or rollers, such as 31, may be provided on the pins 30, and these pins and rollers reciprocate in the guideways 6 of the main frame during the reciprocation of the numbering 20 head and serve to guide the latter in the main frame.

The means for inking the characters on the numbering wheels will now be described.

The inking pad, designated generally 32, 30 is pivotally mounted, as by means of the rod 33, on the main frame. The inking pad includes a pan or recessed portion for holding the pad proper 34, which may be of suitable material, such as felt, for holding the 35 ink. Resilient means, such as the spring 35, is provided for urging the inking pad into engagement with the numbering wheels.

I have also provided means for holding the inking pad in a convenient position to 40 be re-inked. As shown particularly in Figs. 7 and 8, a latch 36 is mounted on one of the members, preferably the main frame, as at 37. In order to prevent rotation of the latch on its mounting I have shown a pin 45 38 secured to the latch and passing through an aperture in the frame. This projecting pin 38 also serves as a convenient means for moving the latch. When it is desired to re-ink the pad, the latter is moved to the 50 position indicated in Figs. 7 and 8 and the latch 36 pushed in, as by means of the pin 38, into engagement with a part of the pad. In the form shown, the pad has projecting ears 39, which serve to contact with the latch 55 for holding the pad in proper position. The pad may be released by simply withdrawing the latch from engagement with the ear 39, and the spring 35 will then snap the pad back to normal position.

60 The comb for rotating the numbering wheels is actuated by means of pins projecting into the main frame 5. In the form shown pins 40 are provided for contacting with the upper edge of the comb yoke 28, 65 and pins 41 are provided for contacting

with the lower edges of the yoke. If desired, suitable rollers may be held on the pins 40 and 41 for reducing the friction between the comb yoke and the pins.

It is often desirable to hold the numbering head in a depressed position. For this purpose I have shown the actuating rod 12 provided with a recess 42, and the frame 5 is provided with a pivotally mounted plate 43 for co-action with the shoulder formed 75 by the recess 42 for holding the numbering head depressed against the tension of the spring 7.

The operation of my machine is as follows:

The numbering head being in the uppermost position, as shown, for example, in Fig. 3, the inking pad will be urged into engagement with the numbering wheels and the pad proper will, of course, deposit ink 85 on the characters. When the head is depressed by means of the knob 13 a part of the numbering head will contact with a part of the inking pad, in the present disclosure, with the ears 39, and the inking pad will 90 be moved to the position indicated in Fig. 4. When the numbering head is depressed the lower edge of the yoke 28 will contact with the pin or roller 41 and move the comb into engagement with a different rotating tooth 95

on one of the numbering wheels. When the knob 13 is released the spring 7' will raise the numbering head and the upper edge of the yoke 28 will contact with the pin or roller 40 and one or more numbering wheels 100 will be rotated the desired distance to bring a different character to the printing position.

The fixed pins or abutments 40, 41 form a cheap means for actuating the lug 27 and are particularly useful in a structure 105 such as shown in the drawings, for the reason that in this construction the comb is operated on both the up and the down strokes by means of the pins, and the only changes necessary for duplication or consecutive numbering are to move the comb 29 and hold the latter in various positions by any suitable means, such as a pin projecting through any one of the apertures in the ear carried by the comb member, as shown in Figs. 3, 4 and 7. During the up-stroke of the numbering head the inking pad will be urged in one direction by means of the spring 35, and when the numbering head is about at the upper limit of its stroke, the felt pad 34 will be in engagement with the characters on the numbering wheels, as shown in Figs. 1, 2, and 3.

It will be seen that the characters are inked just before they are to print, and the characters in the printing position will always be inked while the machine is standing idle.

It will, of course, be obvious that some features of my invention may be omitted,

and that the same may be used in connection with numbering machines of different types from that shown.

While I have described in detail a preferred form of my invention, I wish it to be understood that various changes and modifications may be made within the scope of the appended claims.

I claim:

10 1. In a numbering machine, a U-shaped frame, stationary abutment pins on said frame, a numbering head reciprocable in said frame and carrying numbering wheels, a yoke pivoted to said numbering head and carrying a comb, and a spring for urging the numbering head in one direction, said yoke being adapted to contact with the stationary abutment pins projecting from said frame for moving the yoke on both the up 15 and down stroke thereof for shifting the numbering wheels.

2. In a numbering machine, a U-shaped frame, stationary abutment pins on said frame, rollers carried by said pins, a numbering head reciprocable in said frame and carrying numbering wheels, a yoke pivoted to said numbering head and carrying a comb, and a spring for urging the numbering head in one direction, said yoke contacting with 25 said rollers on said stationary abutment pins projecting from said frame for moving the yoke on both the up and down stroke thereof for shifting the numbering wheels.

3. In a numbering machine, a frame, a numbering head reciprocable in said frame and carrying numbering wheels, a spring for urging said numbering head in one direction, a sheet metal cover for one side of said numbering head and secured thereto and movable 30 bodily therewith, an inking pad pivoted to the main frame, and a spring for urging said pad into engagement with the numbering wheels, said inking pad having a part thereof for contact with said numbering head whereby, upon one stroke of the numbering head, the inking pad will be withdrawn from 35 contact with the numbering wheel.

4. In a numbering machine, a frame, a numbering head reciprocable in said frame and carrying numbering wheels, means for inking said wheels, a spring for urging said numbering head in one direction, a sheet metal cover for one side of said numbering head and movable bodily therewith, said 40 sheet metal cover having a curved housing portion partially encircling the lower sides of said wheels.

5. In a numbering machine, a frame, a numbering head reciprocable in said frame and carrying numbering wheels, means for inking said wheels, a spring for urging said numbering head in one direction, a sheet metal cover for one side of said numbering head and movable bodily therewith, said 50 cover having a flange thereon interfitting

with a part of said numbering head, and means for securing said cover in place on said numbering head.

6. In a numbering machine, a frame, a numbering head reciprocable in said frame, 70 a spring for urging said numbering head in one direction, an inking pad pivoted to said frame, a spring for urging said inking pad into engagement with said numbering head, and a movable latch on said frame and 75 adapted to be moved into engagement with said inking pad for holding the latter in position to be re-inked.

7. In a numbering machine, a frame, a numbering head reciprocable in said frame, 80 a spring for urging said numbering head in one direction, an inking pad pivoted to said frame, a spring for urging said inking pad in one direction, and means carried by said frame and movable into position to engage 85 beneath the inking pad when the latter is swung outwardly for holding said inking pad in position to be re-inked.

8. In a numbering machine, a frame, a numbering head reciprocable in said frame 90 and carrying numbering wheels, an inking pad pivoted to said frame, a spring for urging the pad into engagement with said wheels, said pad having an ear projecting therefrom, and a latch slidably but non- 95 rotatably mounted on said frame adapted to contact with said ear for holding the pad in position to be re-inked.

9. In a numbering machine, a frame, a numbering head reciprocable in said frame, 100 said head including a U-shaped yoke, a shaft carrying numbering wheels, and a side plate fitting each end of the shaft and holding the numbering wheels in place thereon, said plates being secured to said U-shaped frame 105 whereby the numbering wheels will be held in the head.

10. In a head for a numbering machine, a substantially U-shaped yoke, a shaft carrying numbering wheels, a plate on each end of said shaft for holding the wheels in place thereon, and means for securing the plates within said yoke whereby the wheels will be held in the head.

11. In a numbering head for a numbering machine, a numbering head frame, a shaft carrying numbering wheels, and a plate on each end of said shaft for holding the wheels in place, said frame and plates having co-operating tongues and recesses for positioning the parts relatively to each other.

12. In a numbering head for a numbering machine, a numbering head frame, a shaft carrying numbering wheels, a plate on each end of said shaft for holding the wheels in 125 place, said frame and plates having co-operating tongues and recesses for positioning the parts relatively to each other, and means for securing said plates and head together.

13. In a numbering head for a numbering machine, a numbering head frame, a shaft carrying numbering wheels, a plate on each end of said shaft for holding the wheels in place, and means for securing said plates to said frame.
14. In a numbering head for a numbering machine, a numbering head frame, a shaft carrying numbering wheels, a plate on one end of said shaft, means for preventing rotation between said plate and shaft, said plate being secured to said head frame.
15. In a numbering head for a numbering machine, a numbering head frame, a shaft carrying numbering wheels, a plate on one end of said shaft, and means for securing said plate in said numbering head frame whereby the shaft will be held in said frame.
16. In a numbering head for a numbering machine, a numbering head frame, a shaft carrying numbering wheels, means secured to said numbering head frame for holding said shaft and numbering wheels in place in said head frame, and including a plate at each end of said shaft.
17. In a numbering machine, a frame, a numbering head reciprocable in said frame, said head including a substantially U-shaped frame, a shaft carrying numbering wheels, a plate on each end of said shaft, coöoperating lugs and recesses on said U-shaped frame and plates for positioning the latter, a sheet metal cover for one side of said numbering head, means for securing said cover and said plates in place on said U-shaped frame and means for rotating said numbering wheels.

ALBERT J. MARKS.
